UNITED STATES PATENT OFFICE.

CHARLES F. TERNEY, OF BUFFALO, NEW YORK.

BARREL-VALVE.

938,288.

Specification of Letters Patent. Patented Oct. 26, 1909.

Application filed November 13, 1908. Serial No. 462,899.

To all whom it may concern:

Be it known that I, CHARLES F. TERNEY, a citizen of the United States, residing at Buffalo, in the county of Erie and State of New York, have invented a new and useful Improvement in Barrel-Valves, of which the following is a specification.

This invention relates to a valve or bung for tapping beer or other liquids from a barrel by air pressure.

The object of this invention is to produce a valve of this character which is simple and inexpensive in construction and reliable in operation, which will securely close the barrel when the tapping rod or pipe is withdrawn therefrom and which can be readily dismembered and assembled for cleaning or repairing.

In the accompanying drawings consisting of 2 sheets: Figure 1 is a vertical longitudinal section of my improved valve in connection with a tap showing the parts in the position which they occupy when the valve is opened and the tapping rod is pushed into the barrel. Fig. 2 is a vertical transverse section at right angles to Fig. 1 and taken on line 2—2 in that figure. Fig. 3 is a vertical section showing the bushing in the same position as that indicated in Fig. 1 but the tap, plug and connecting parts turned into a position corresponding to Fig. 2, which position the parts occupy when the valve is closed. Fig. 4 is a bottom plan view of the tap. Fig. 5 is a top plan view of the bushing and the head of the plug, the latter being in the position which it occupies when the valve is closed and the tap is removed therefrom. Fig. 6 is a view similar to Fig. 5 with the head of the plug removed. Fig. 7 is a bottom plan view of the head of the plug. Fig. 8 is a vertical longitudinal section of the bushing with the plug and connecting parts removed therefrom.

Similar letters of reference indicate corresponding parts throughout the several views.

A represents the bushing of the valve or bung which is preferably of circular form and provided on its periphery with a screw thread *a* whereby the same is secured within an opening in the head of the barrel and also provided at its inner or front end with a head B having a port or opening *b* on one side of its center. On the outer or rear side of the head around its port the same is raised slightly, forming a valve seat *b*¹, as shown in Figs. 1, 3 and 8.

Within the front part of the bore of the bushing the same is provided with an internal screw thread *c* which preferably trends toward the left and within the outer or rear part of its bore the bushing is provided on diametrically opposite sides with tightening ribs *d*, *d* the front or inner sides *d*¹ of which are inclined, as shown in Fig. 8. The ribs *d* are arranged outside or beyond the diameter of the screw thread *c* of the bushing.

E represents the plug whereby the port in the head of the bushing is opened and closed. The plug is provided with an external screw thread *e* which engages with the internal screw thread of the bushing.

In one part of the screw plug at the side of its center the same is provided with an opening *f* which is arranged parallel to the axis thereof and on another part of the screw plug at the side of its center the same is provided with a stopper or gate G. Upon turning the screw plug toward the right the same is moved axially outward or away from the head of the bushing by the screw connection between these parts and the opening in the plug is brought into alignment with the port of the bushing head, while upon turning the screw plug toward the left the same will move axially inward toward the head of the bushing and the stopper is caused to engage with the seat around the outer end of the port *b* and close the same. Owing to the screw thread connection between the plug and the bushing, the stopper engages with the valve seat only during the last part of the turning movement of the plug toward the left, and upon turning the screw plug toward the right the stopper recedes from the valve seat during the first part of this movement, thereby enabling the valve to be operated very easily and avoiding undue wear on the same.

The stopper may be constructed of rubber or any other suitable material and secured to the plug in various ways. As shown in the drawings, the same is constructed in the form of a flat plate which is provided on its outer or rear side with a dove tail portion *g* which engages with a correspondingly formed seat *h* extending radially inward from the periphery of the plug on the front side thereof, as shown in Figs. 1, 2, 3 and 6. In order to prevent the stopper from being engaged with the valve seat with undue pressure upon closing the valve, the front or inner side of the plug is provided with a

stop or projection *i* which is adapted to engage with a bearing surface or seat *i*¹ on the rear side of the bushing head adjacent to its port, as shown in Fig. 3.

- 5 J represents a head or cover plate secured to the outer end of the plug and provided on diametrically opposite sides of its periphery with laterally projecting or peripheral lugs *j*, *j* which are adapted to engage with the 10 ribs *d* of the bushing for preventing the plug from being removed from the bushing. The plug head is provided on one side of its center with an opening *j*¹ which is in line with the opening *f* of the plug. On its 15 front side the plug head is provided with forwardly or inwardly projecting lugs *K*, *K* which engage with notches or seats *l*, *l* at the rear end of the plug, thereby interlocking the plug and its head and compelling the same to turn together. The bushing and its head are secured against displacement relatively to each other in the direction of the axes of the same by means of screws *m* passing through the head from the outer 20 side thereof and entering threaded openings in the rear end of the plug. In assembling the parts, the plug is first screwed in the bushing until its outer or rear end is separated a suitable distance from the front side 25 of the ribs of the bushing. The diameter of the coöoperating threads of the bushing and plug is less than the diameter at the inner edge or bore of the ribs of the bushing. After the screw plug has been thus introduced in the bushing, the plug head is passed axially into the bushing while the lugs of the head are in alinement with the spaces between the opposing end of the ribs of the bushing and then the plug head is 30 interlocked with the plug by engaging its front lugs with the recesses of the plug and is secured to the latter by means of the screws *m*. After the plug head has been thus applied to the plug the latter cannot be 35 fully unscrewed from the bushing, inasmuch as the peripheral lugs *j*, *j* of its head will strike the internal ribs *d* of the bushing.
- N represents the tubular body of the tap which is arranged eccentrically on the rear or outer side of a coupling head O and which is provided with a laterally projecting nozzle *p*. The body of the tap is adapted 40 to receive the tapping tube or pipe Q whereby the liquid is to be withdrawn from the barrel and the nozzle is adapted to receive a tube or conduit through which compressed air is delivered into the barrel for forcing or expelling the liquid therein through the tapping rod. The coupling head O is provided on its front side with a tubular shank *r* which is adapted to enter the outer or rear 45 end of the bushing and around this bushing the coupling head is provided on its front side with a packing ring *r*¹ of rubber or other suitable material which is adapted

to engage with the outer end of the bushing and form a tight joint between the same and the coupling head while the tapping device is in operation.

Means are provided for compelling the tap to turn with the plug for opening and closing the valve and also detachably connecting the same with the bushing. The preferred means for this purpose as shown in the drawings consist of a pair of seats or 70 recesses *s*, *s* formed within the bore of the shank *r* and adapted to receive outwardly projecting lugs *s*¹, *s*¹ formed on the outer side of the plug head and two coupling lugs *t*, *t* projecting laterally from diametrically 75 opposite sides of the periphery of the shank and adapted to coöperate with the tightening ribs *d* of the bushing. In attaching the tap to the plug and bushing, the tap is first placed with its laterally projecting lugs *t*, *t* 80 in alinement with the spaces between the ribs *d* of the bushing and then moved forwardly so that its shank enters the outer end of the bushing and its laterally projecting lugs *t*, *t* pass through the spaces between the ribs and its recesses *s*, *s* receive the coupling lugs *s*¹, *s*¹ of the plug head. After 85 the tap has been thus applied to the bushing and plug it is turned toward the right, thereby causing the laterally projecting lugs *t*, *t* of the shank to engage with the inclined front sides of the ribs *d* of the bushing and cause the head of the tap and the packing *r*¹ to be drawn firmly against the outer end of the bushing, thereby forming a tight connection 90 between these parts. While thus turning the tap for connecting the same with the bushing, the plug is also turned by means of the interlocking lugs and recesses *s*, *s*¹, thereby causing the stopper of the plug 95 to be moved away from the port of the bushing head and the opening of the plug and plug head to be brought in alinement with the port of the bushing head. In the coupled position of the tap and plug, the 100 body of the tap is in line with the openings of the plug and plug head, so that when the valve is opened, the port of the bushing head, the openings of the plug and plug head, and the tubular body of the tap are 105 all in alinement.

Before turning the tap for opening the valve, the tapping pipe or rod Q is pushed part way through the stuffing box *q* at the outer end of the tap and after the latter has 110 been fully turned toward the right together with a plug, the tapping rod is pushed inwardly through the openings of the plug and plug head, the port of the bushing and into the barrel for withdrawing the liquid 115 therefrom.

When disconnecting the tapping device from the barrel, the tapping rod is first withdrawn from the barrel and into the body of the tap and then the latter is turned 120

toward the left until the tightening lugs on its shank are disengaged from the inclined inner sides of the bushing ribs and brought into alignment with the spaces between the 5 same. Thereafter the tap may be withdrawn axially from the bushing and the plug head. While thus turning the tap toward the left for disengaging the same from the plug, the latter is also turned in 10 the same direction for bringing its stopper over the valve seat of the bushing and closing the valve.

It will be noted that in the act of attaching the coupling to the bushing the valve 15 will be opened and that these parts can not be again uncoupled until the valve has been closed.

I claim as my invention:

1. A barrel valve comprising a bushing 20 having an internal screw thread and a head provided with an eccentric port, and a plug having an external screw thread engaging with the internal thread of the bushing, an eccentric port and an eccentric stopper, the 25 eccentric port of said plug being brought into alignment with the port of the bushing upon turning the plug in one direction and withdrawing the same from said head, and the stopper of the plug being engaged with 30 the socket on said head around the port therein upon turning the plug in the opposite direction and moving the same toward said head.

2. A barrel valve comprising a bushing 35 having an internal screw thread and a head provided on one side of its center with a port, a plug having an external screw thread engaging with the internal thread of the bushing and provided in one of its parts at 40 the side of its center with a port which is adapted to register with said port of the bushing upon turning the plug in one direction and provided in another part at the side of its center with an undercut socket, and a 45 stopper arranged in said socket and adapted to move over the port in said bushing upon turning the plug in the opposite direction.

3. A barrel valve comprising a bushing having an internal screw thread and a head 50 provided on one side of its center with a port, a plug having an external screw thread engaging with the internal thread of the bushing and provided in one of its parts at the side of its center with a port which is 55 adapted to register with said port of the bushing upon turning the plug in one direction and provided in another part at the side of its center with an undercut socket, a stopper arranged in said socket and adapted to 60 move over the port in said bushing upon turning the plug in the opposite direction, and a stop arranged on the plug adapted to engage with said head upon turning the 65 plug in the direction for moving the stopper over the port in the bushing.

4. A barrel valve comprising a bushing having an internal screw thread and a head provided on one side of its center with a port, a plug having an external screw thread engaging with the internal thread of the 70 bushing and provided in one of its parts at the side of its center with a port which is adapted to register with said port of the bushing upon turning the plug in one direction and provided in another part at the 75 side of its center with an undercut socket of dovetail form which extends inwardly from the periphery of the plug and a stopper having a dovetail portion which is seated in said socket, said stopper being adapted to 80 move over the port in the bushing upon turning the plug in the opposite direction.

5. A barrel valve comprising a bushing having a head at its inner end which is provided with a port on one side of its center, 85 an internal screw thread in the front part of its bore and a tightening rib arranged outside of the diameter of said threads in the outer part of the bore of said bushing, a plug having an external screw thread engaging the internal thread of the bushing, a port in one of its parts at the side of its center adapted to register with the port of said bushing upon turning the plug in one direction and a stopper on another part of the 90 plug at the side of its center and adapted to be moved over the port of the bushing upon turning the plug in the opposite direction, and a stop detachably secured to the outer end of said plug and adapted to engage said 100 rib upon unscrewing the plug from the bushing.

6. A barrel valve comprising a bushing having a head at its inner end which is provided with a port and one side of its center, 105 an internal screw thread in the front part of its bore and a tightening rib arranged outside of the diameter of said threads in the outer part of the bore of said bushing, a plug having an external screw thread engaging the internal thread of the bushing, a port in one of its parts at the side of its center adapted to register with the port of said bushing upon turning the plug in one direction, and a stopper on another part of the 110 plug at the side of its center and adapted to be moved over the port of the bushing upon turning the plug in the opposite direction, and a head secured to the outer end of said plug and having a lug projecting laterally beyond said threads and adapted to engage said rib upon unscrewing the plug. 115

7. A barrel valve comprising a bushing having a head at its inner end which is provided with a port on one side of its center, 120 an internal screw thread in the front part of its bore and tightening ribs arranged outside of the diameter of said threads in the outer part of the bore of said bushing, a plug having an external screw thread engaging the inter- 125

nal thread of the bushing, a port in one of its parts at the side of its center adapted to register with the port of said bushing upon turning the plug in one direction and a stopper on another part of the plug at the side of its center and adapted to be moved over the port of the bushing upon turning the plug in the opposite direction, and a head secured to the outer end of said plug and having laterally projecting lugs adapted to engage

with the lugs of the bushing and provided on its front side with lugs engaging with recesses in the plug and on its outer side with lugs adapted to engage with recesses in a tap.

Witness my hand this 12th day of November, 1908.

CHARLES F. TERNEY.
